[57] CLAIM

The ornamental design for an entertainment cabinet unit, as shown and described.

DESCRIPTION

FIG. 1 is a front elevational view of an entertainment cabinet unit showing my new design;

FIG. 2 is a top plan view thereof;

FIG. 3 is a front elevational view of a second embodiment of the entertainment cabinet unit shown in FIG. 1, the top view being identical to FIG. 2;

FIG. 4 is a front elevational view of a third embodiment of the entertainment cabinet unit shown in FIG. 1; and FIG. 5 is a side elevational view of FIGS. 1, 3 and 4, the opposite sides being a mirror image thereof.

The rear of the unit of FIGS. 1, 3 and 4 is flat and unornamented.

FIG. 3

FIG. 2
